PRESSURIZED LIQUID FILTERING VESSEL OR
SIMILAR ARTICLE

Edward A. Smith, Glenville, Conn., assignor to GAF
Corporation, New York, N.Y.

Filed Nov. 30, 1972, Ser. No. 310,848

Term of patent 14 years

Int. Cl. D23—01

U.S. Cl. D23—4

FIG 1 is a top plan view of a pressurized liquid filtering vessel showing my new design;

FIG. 2 is a front elevation thereof;

FIG. 3 is a right side elevation thereof;

FIG. 4 is a left side elevation thereof; and

FIG. 5 is a bottom plan view thereof.

I claim:

The ornamental design for a pressurized liquid filtering vessel or similar article, as shown.
